UNITED STATES PATENT OFFICE.

GUSTAF DAVID SUNDSTRAND, OF ROCKFORD, ILLINOIS, ASSIGNOR TO ROCKFORD MILLING MACHINE COMPANY, OF ROCKFORD, ILLINOIS, A CORPORATION OF ILLINOIS.

KNEE FOR MILLING MACHINES.

Application filed January 10, 1919. Serial No. 270,510.

To all whom it may concern:

Be it known that I, GUSTAF DAVID SUNDSTRAND, a citizen of the United States, residing at Rockford, in the county of Winnebago and State of Illinois, have invented 5 certain new and useful Improvements in Knees for Milling Machines, of which the following is a specification.

The object of this invention, generally 10 stated, is to provide improved means for controlling the adjustment of the knee by power and for controlling the power feed of the saddle.

In the accompanying drawings, Figure 1 15 is a plan view of a knee embodying the features of my invention, a portion of the milling machine column being shown in section. Fig. 2 is a sectional view taken in the plane of dotted line 2—2 of Fig. 1. Fig. 3 is a section 20 view taken in the plane of dotted line 3—3 of Fig. 7. Fig. 4 is a side elevation of the knee. Fig. 5 is a section on line 5—5 of Fig. 2. Fig. 6 is a view taken in the plane of dotted line 6—6 of Fig. 7. Fig. 7 25 is a fragmental front end elevation of the knee. Fig. 8 is a view taken in the plane of dotted line 8—8 of Fig. 1.

In the drawings, 1 represents a portion of 30 the milling machine column. 2 is the ordinary vertical guide on the front wall of the column. The knee 3 is provided at its rear side with means to slidably engage the guide 2 in the usual manner.

The means for raising and lowering the 35 knee 3 comprises a screw 4, the lower portion of which engages a nut (not shown) in the usual manner. To the upper portion of the screw is secured a bevel gear wheel 5 (Fig. 3) that meshes with a bevel pinion 6 which is mounted upon a shaft 7 in the knee. Rigid with the bevel pinion 6 is a spur gear wheel 8 that meshes with a similar gear wheel 9. The gear wheel 9 is rigid with a hub or sleeve 10 which is rotatably mounted upon a shaft 11 carried by the knee. Fixed upon the shaft 11 is a spur gear wheel 12 which meshes with a pinion 13 (Fig. 1) formed upon a sleeve 14 (Fig. 6) which is rotatably mounted upon a 45 shaft 15 supported in the knee. To the shaft 15 is rigidly secured a spur gear wheel 16 which meshes with an intermediate pin-

ion 17 (Fig. 8). The pinion 17 meshes with a gear wheel 18 mounted on a shaft 19 carried by the knee. The gear wheel 18 meshes with an intermediate gear 20 (Fig. 8) which in turn meshes with a pinion 21 rotatably mounted on a shaft 22 supported by the knee. The shaft 22 is driven in any suitable way, as by means of the usual extensible shaft (not shown). A reversing mechanism 23 (Fig. 1) of common form transmits power from the shaft 22 to the pinion 21.

The means for communicating power 65 from the shaft 15 to the pinion 13 comprises a clutch sleeve 24 (Fig. 6) mounted for sliding movement upon said shaft, but connected to rotate with the shaft by means of a spline 25. The adjacent ends of the sleeves 14 and 24 are provided with clutch faces. The clutch formed by the parts 14 and 24 will be hereinafter referred to as the primary clutch. In the sleeve 24 is an annular peripheral groove 26 to receive 70 a stud 27 (Fig. 2) upon an arm 28, said arm being fixed to a transverse rock shaft 29 carried by the knee. Fixed to the shaft 29 is an arm 30 (Fig. 5) having a pin 31 that lies in a notch in a tripping pin 32. 80 The tripping pin 32 is mounted for vertical sliding movement in the knee. An arm 33 is connected to the tripping pin 32 by means of a pin 34 lying in a notch in the tripping pin. The arm 33 is rigid with a hand-lever 85 35 which is rotatably mounted upon a rock-shaft 36 carried by the knee. Rigid with the lever 35 and arm 33 is an arm 37 which has a pin and notch connection with a tripping rod 38, said tripping rod being mounted in the knee for horizontal movement. The rear end of the tripping rod 38 is arranged to engage suitable tripping devices, such for example, as the device 39 (Fig. 1) on the column 1. The devices 39 are located 90 in position to limit the movement of the knee by causing longitudinal movement of the tripping rod 38 and consequently movement of the clutch sleeve 24 out of engagement with the clutch sleeve 14. It will be seen that disengagement of the sleeve 24 from the sleeve 14 will interrupt the transmission of power to the feed screw 4. The movement of the knee may be started and

stopped at will by means of the hand-lever 35. The direction of movement of the knee may be reversed by operating the reverse mechanism 23 in the well known manner.

5 The means for connecting the pinion 9 (Fig. 3) to the shaft 11 at will comprises a secondary clutch sleeve 40 which is slideable longitudinally of said shaft but is arranged to rotate therewith by means of a spline 41. 10 One end of the sleeve 40 is provided with a clutch face to engage a clutch face on the adjacent end of the sleeve 10. The rock shaft 36 (Fig. 2) carries a crank arm 42 having a pin 43 that lies within an annular groove 44 (Fig. 3) in the sleeve 40. Rigid with the outer end of the rock-shaft 36 is a crank 45 by means of which the shaft 36 may be rocked to move the sleeve 40 into and out of clutch engagement with the 20 sleeve 10.

The saddle 46 is slidably mounted upon the knee 3 for horizontal movement toward and away from the column 1, the saddle being mounted upon a guide 47 on the knee. 25 The saddle is arranged to be moved upon its guide 47 by means including a nut 48 (Fig. 3) fixed in a lug 49 that projects downwardly from the saddle into a slot 50 in the top of the knee. The nut 48 engages a screw 51 having a squared forward end to receive a crank (not shown) by means of which the saddle may be manually adjusted. The power means for rotating the screw 51 comprises a pinion 52 fixed upon said screw 35 and meshing with pinion 53 which is loosely mounted upon the shaft 11. The pinion 53 is provided with a hub or sleeve 54 having a clutch face arranged for engagement by a clutch face formed upon the adjacent end 40 of the secondary clutch sleeve 40. It will be seen that by means of the crank 45 the clutch sleeve 40 may be moved into position to drive the knee-adjusting gear 9 or the saddle-feeding gear 53, and that the 45 clutch sleeve 40 may also be placed into the neutral position represented in Fig. 3. In Fig. 4 the crank 45 is shown in neutral position.

Means may be provided for automatically 50 throwing out the saddle feed at any desired point. Herein are shown two fixed projections 55 and 56 (Fig. 4) and an adjustable tripping block 57 upon the saddle, the tripping elements 55, 56 and 57 being located 55 so that they may be carried into engagement with the conical upper end of the tripping pin 32. It will be seen that when the tripping pin 32 is thus engaged, the shaft 29 will be rocked in the direction to throw 60 out the primary clutch sleeve 24, thus stopping the saddle. The screw 51 may then be manually rotated in the reverse direction to move the tripping element (55, 56 or 57) clear of the pin 32, after which the direction 65 of the rotation of the pinion 21 may be re-

versed by means of the mechanism 23, and the saddle feed thrown in by depressing the hand-lever 35.

Means may be provided for manually operating the screw 4 to raise or lower the 70 knee as, for example, a shaft 58 carried by the knee and having a bevel gear 59 that meshes with the bevel gear 5. The outer end of shaft 58 is squared to receive a crank. 75

In case the tool breaks or if, for any other 75 reason, it is desired to stop the movement of the saddle, the hand-lever 35 is raised, thereby throwing out the primary clutch. The connections between the lever 35 and the primary clutch sleeve 24 are such that 80 the primary clutch may be thrown in and out very promptly and rapidly.

The primary clutch lever 35 controls the transmission of power to the secondary clutch sleeve 40. The secondary clutch- 85 operating crank 45 distributes the power of the clutch sleeve 40 to the knee-adjusting mechanism and the saddle-feeding mechanism. Thus it will be evident that both the lever 35 and the crank 45 must be operated 90 before the knee can be adjusted by power and before the saddle can be fed by power. Consequently, when the crank 45 is in neutral position, there is no danger of the saddle-feed or the knee adjustment being accidentally thrown in by inadvertent operation of the lever 35, as by reason of something falling on said lever. 95

The hand lever 35 and the crank 45 are 100 close together, and thus may be conveniently operated without a shifting of position of the workman.

I would have it understood that the foregoing detailed description of one embodiment of my invention has been given for the 105 sake of clearness of understanding and not for the purpose of limiting the invention, the scope of the invention being indicated in the appended claims.

In certain of the claims I have used the 110 term "power element" to denote broadly any source of power. In the present embodiment, the pinion 21 may be considered as the source of power.

I claim as my invention:

1. A milling machine having, in combination, a knee, a saddle on the knee, a power-element on the knee, knee-adjusting mechanism, saddle-feeding mechanism, a secondary clutch controlling the transmission of 115 power to said mechanisms, a primary clutch controlling the transmission of power from the power-element to the secondary clutch, and separate manipulative devices for said 120 clutches, said devices being mounted on the same side of the knee and close together.

2. A milling machine having, in combination, a knee, a saddle on the knee, knee-adjusting mechanism, saddle-feeding mechanism, a secondary clutch element movable 125

into driving engagement with either of said mechanisms alternately, and means for energizing said clutch element.

3. A milling machine having, in combination, a knee, mechanism for raising and lowering the knee, a power element on the knee, and a power-transmission between the power element and said mechanism, said transmission including two independently-operable clutches arranged in series, the first clutch being adapted to deliver power to the second clutch and the second clutch being adapted to transmit power to either of two independent mechanisms.

15 4. A milling machine having, in combination, a power element, separate control means for moving the work on the machine in each of two directions at right angles to each other, a controlled transmission adapted to receive power from said power element and a second controlled transmission adapted to receive power from said first transmission and convey it to either (or neither) of said control means.

25 5. A milling machine having, in combination, a slideable knee and means for sliding said knee, a slideable saddle and means for sliding said saddle, a power element and connections adapted to slide either said knee or said saddle but not both.

35 6. A milling machine having, in combination, a knee, a power transmission from the knee, said transmission including two clutches arranged in series, the first clutch adapted to deliver power to the second clutch and the second clutch adapted to deliver power to either of two independent feeding mechanisms, each clutch comprising a movable element, two rock shafts mounted on the knee and extending beyond the side of the knee, each shaft being connected to one of said elements, and means for independently rocking said shafts.

45 7. A milling machine having, in combination, a knee, a saddle on the knee, a shaft extending from front to rear of the knee, means for rotating the shaft, knee-adjusting mechanism including an element rotatable on said shaft, saddle-feeding mechanism including an element rotatable on the shaft, and a clutch member slideable on the shaft into driving engagement with either of said elements.

55 8. A milling machine having, in combination, a knee, a power element on one side of the knee, a power transmission on the knee including two clutches, a casing on the other side of the knee and manually-controlled elements projecting from said casing for operating said clutches.

65 9. In a milling machine, in combination, a source of power, a control clutch, a table, transmission from said control clutch to said table for moving said table in either one of two mutually perpendicular direc-

tions, a shaft controlling said control clutch, and safety means for limiting the movement of said table, said safety means comprising two elements each slideable at an angle to the direction of table motion over which it exerts control, and each connected to said control shaft.

10 10. A milling machine having, in combination, a knee, means for moving said knee, a saddle on said knee, means for moving said saddle, power transmission to said moving means including a plurality of shafts rotating at different speeds, a control clutch located in said knee on a shaft having a relatively high speed, and a single distributing clutch dependent upon said control clutch for power adapted to control the transmission of power to said knee and saddle and located on a shaft having a slower speed than the shaft carrying said control clutch.

15 11. A milling machine having, in combination, a knee, means for moving said knee vertically, a saddle on said knee, means for moving said saddle, a power transmission to said moving means including a plurality of shafts rotating at different speeds, a control clutch located on a shaft having a relatively high speed, and a single distributing clutch driven through said control clutch located on a shaft having a slower speed than the shaft carrying said control clutch, said distributing clutch being adapted to deliver power directly to said knee-moving means or to said saddle-moving means, but not to both.

20 12. In a milling machine, in combination, a source of power, a control clutch, a column, a knee slideable on said column, a saddle slideable horizontally on said knee, distributing transmission including clutch elements for moving said knee and saddle by power received from said control clutch, a control shaft carried by said knee for controlling said control clutch, a vertically slideable element carried by said knee adapted to contact with projections on said saddle and operatively connected to said control shaft to prevent movement of said saddle past a predetermined limit in either direction, and a horizontally slideable element carried by said knee adapted to make contact with portions of said column and operatively connected to said control shaft to limit the displacement of said knee in either direction.

25 13. The combination recited in claim 12 in which said vertically slideable element is directly connected to said control shaft, and said horizontally slideable element is connected to said vertical element to actuate said vertical element and thereby actuate said control shaft.

30 14. The combination recited in claim 13 in combination with a control shaft for said

distributing transmission, and in which the connection between said horizontally slid-able element and said vertically slidable element includes a pivoted connecting element, 5 the control shaft for said distributing trans-mission serving as a pintle for said pivoted connecting element.

15. A milling machine having, in combi-nation, a column, a vertically slidable knee 10 on said column, means for sliding said knee, a horizontally slidable saddle on said knee, means for sliding said saddle, a rotating shaft, a clutch adapted to connect said shaft directly to the means for sliding said knee or the means for sliding said saddle, a second shaft rotating at a higher speed than said first-mentioned shaft, and a control clutch 15 on said second-mentioned shaft adapted to deliver power to said first-mentioned shaft.

20. 16. The combination recited in claim 15 in combination with automatic stops adapted to throw out said control clutch when said knee has been moved past a predeter-mined point.

25. 17. The combination recited in claim 15 in combination with automatic control stops adapted to throw out said control clutch when said saddle has been moved past a pre-determined point.

30. 18. The combination recited in claim 15 in combination with a single element opera-tively connected to said control clutch, and means for moving said element to discon-nect said control clutch when either said knee or said saddle have been moved past predetermined points.

35. 19. A milling machine having, in combi-nation, a reversing clutch adapted to re-cieve power from a suitable source to drive a transmission shaft in either direction, a control shaft driven from said transmission shaft, a control clutch on said control shaft, a distribution shaft adapted to be driven by said control shaft at a slower rate of speed than that of said control shaft, and a dis-tribution clutch on said distribution shaft adapted to selectively connect said shaft to various feeding mechanisms.

40. 20. A milling machine having, in combi-nation, a reversing clutch adapted to receive power from a suitable source to drive a transmission shaft in either direction, a control shaft driven from said transmission shaft, a control clutch on said control shaft, a distribution shaft adapted to be driven by said control shaft at a slower rate of speed than that of said control shaft, and a distribution clutch on said distribution shaft adapted to connect said shaft to either one 45 of two independent feeding mechanisms, but not to both.

45. 21. A milling machine having, in combi-nation, a reversing clutch adapted to re-cieve power from a suitable source to drive a transmission shaft in either direction, a

control shaft driven from said transmission shaft, a control clutch on said control shaft, a distribution shaft adapted to be driven by said control shaft at a slower rate of speed than that of said control shaft, and a distribution clutch on said distribution shaft adapted to connect said shaft to an intermediate transmission shaft, a work supporting element, a shaft operatively connected to said work supporting element to raise and lower the same, and an operative trans-mission between said intermediate transmis-sion shaft and the shaft connected to said work supporting element for rotating said last-mentioned shaft at a relatively low speed.

50. 22. A milling machine having, in combi-nation, a knee, a vertical feed screw shaft adapted to raise and lower said knee, a horizontal shaft geared to said vertical feed shaft to rotate at a higher speed than said vertical feed shaft, a distribution shaft carrying a member geared to said horizontal shaft to rotate at a speed not lower than that of said horizontal shaft, a clutch adapt-ed to connect said last-mentioned member with said distribution shaft, a control shaft rotating at a higher rate of speed than said distribution shaft, and a control clutch on said control shaft adapted to connect it to said distribution shaft.

55. 23. The combination recited in claim 22 in combination with a saddle slidable on said knee, and a second rotatable member on said distribution shaft operatively connected to said slidable saddle, said distribution clutch being adapted to connect either of said ro-tatable members to said distribution shaft.

60. 24. A milling machine having, in combi-nation, a column, a knee slidable on said column, a saddle slidable on said knee, means for sliding said knee on said column and means for sliding said saddle on said knee, a power transmission adapted to de-liver power to either of said sliding means, but not both, a control clutch in said trans-mission mechanism adapted to cut off the supply of power from said sliding means, and automatic stops on said column and on said saddle operatively connected through a single rock shaft to said control clutch for throwing out said control clutch.

65. 25. A milling machine having, in combi-nation, a work table, two separate means for feeding said table in mutually perpen-dicular directions, a power transmission to said feeding means, said transmission in-cluding a control shaft, a clutch operated and associated with said control shaft to transmit power therefrom, a transmission shaft adapted to receive power from said clutch, a clutch on said transmission shaft adapted to deliver power to either of said feeding means, a casing, control shafts op-eratively connected to said clutches and ex-

tending into said casing, and means extending into said casing adapted to throw out said control clutch when either of said feeding means has operated to move the work 5 support past a predetermined point.

26. In a milling machine, in combination, two parallel control shafts, a manual control element directly connected to one of said control shafts, and a control transmission 10 for the other control shaft including a rotatable element pivoted on said first mentioned control shaft.

27. In a device of the class described,

in combination, two parallel control shafts, 15 a casing receiving one of said shafts centrally and the other shaft adjacent one edge of the casing, a manual control element mounted on the end of said central shaft and rotatable outside said casing over the face thereof, and a manual control element for 20 the other shaft pivoted on the first shaft and projecting through the wall of said casing.

In testimony whereof, I have hereunto set my hand.

GUSTAF DAVID SUNDSTRAND.
